UNITED STATES PATENT OFFICE

99,362

DESIGN FOR A STEAM SPRAYING APPARATUS

Abraham Newar, Chicago, Ill., assignor to Marvel Appliance Corporation, Chicago, Ill., a corporation of Illinois

Application January 15, 1936, Serial No. 60,604

Term of patent 14 years

To all whom it may concern:

Be it known that I, Abraham Newar, a citizen of the United States, residing at Chicago, in the county of Cook and State of Illinois, have invented a new, original, and ornamental Design for a Steam Spraying Apparatus, of which the following is a specification, reference being had to the accompanying drawing, forming a part thereof.

The figure is a perspective view of the article showing my design.

The two sides opposite those shown in the drawing are of an appearance exactly the same as that of the two sides shown in the drawing, except that there is no sight glass on either of the two sides that are not shown.

I claim:

The ornamental design for a steam spraying apparatus substantially as shown and described.

Signed at Chicago, in the county of Cook and State of Illinois, this 13th day of January, 1936.

ABRAHAM NEWAR.
